UNITED STATES PATENT OFFICE.

ROBERT A. STEWART, OF NEW YORK, N. Y., ASSIGNOR TO THE INDEPENDENT MANUFACTURING COMPANY, OF CHICAGO, ILLINOIS.

DESIGN FOR A DIE-PLATE.

SPECIFICATION forming part of Design No. 30,049, dated January 24, 1899.

Application filed December 28, 1898. Serial No. 700,567. Term of patent 14 years.

To all whom it may concern:

Be it known that I, ROBERT A. STEWART, a citizen of the United States, residing at New York city, in the county of New York and State of New York, have invented and produced a new and original Design for Die-Plates, of which the following is a specification, reference being had to the accompanying drawings.

Figure 1 is an end view of a die-plate showing my design. Fig. 2 is a side view of the same.

As shown in the accompanying drawings, there is a body portion A, from which rise end pieces B, as shown in Fig. 1, and depending from said body are flanges C, as illustrated in Fig. 2.

The side pieces B have peculiarly-shaped apertures D, which terminate at top in straight parallel grooves *d* and at bottom in curved converging grooves *d'*, leaving a partially-circular portion E between them, having near its bottom a round hole *e*.

What I claim as new is—

The design for a die-plate as herein shown and described.

In testimony whereof I affix my signature, in the presence of two witnesses, this 27th day of December, 1898.

ROBERT A. STEWART.

Witnesses:

THOS. E. ROBERTSON,
J. J. NELLIGAN.
